UNITED STATES PATENT OFFICE.

BENJAMIN F. BROWN, OF FITCHBURG, MASSACHUSETTS.

BATH-TUB RAIL.

1,261,759.

Specification of Letters Patent. Patented Apr. 9, 1918.

Application filed July 6, 1915. Serial No. 33,070.

To all whom it may concern:

Be it known that I, BENJAMIN F. BROWN, a citizen of the United States, residing at Fitchburg, county of Worcester, State of Massachusetts, have invented an Improvement in Bath-Tub Rails, of which the following description, in connection with the accompanying drawing, is a specification, like characters on the drawing representing 10 like parts.

This invention relates to a novel construction of bath tub rail.

It is a matter of common knowledge that, in getting into, moving around within and 15 in getting out of bath tubs, many serious accidents have occurred due to the fact that a firm and certain grasp or footing is not afforded. The tub bodies as now made are generally enameled—presenting a surface 20 of glass-like smoothness and, when wet with water carrying soap in solution, every movement with relation to the tub entails danger, especially in the case of young or aged or infirm persons. This novel construction dis- 25 closed effects a safeguard by providing a substantially horizontal means which can be grasped. The same dangers are attendant upon the use of shower bath apparatus where, due to the presence of soap and water 30 upon the glazed base of the inside of the tub, an exceedingly insecure footing is produced. This device has an arm adapted for use in such cases. Swung vertically upward from the tub side into locked position, a se- 35 cure and firm hold is afforded. As bath tubs are manufactured in varying sizes and shapes, this device is made adjustable so as to fit accurately the different tubs.

The object therefore of this invention is 40 to provide a hand rail adapted to be positioned on the side of a bath tub.

Another object is to provide such a bath tub rail with means for adjustably positioning it upon varying shapes and sizes of 45 tubs.

A further object is to provide a transverse bath tub rail so pivoted with relation to the tub that it may be turned substantially perpendicular thereto, to provide a hand rail 50 when the tub is used in connection with shower bath appliances.

With these and other objects in view, as will more fully appear, the invention consists in the novel construction and arrangement of parts hereafter fully described, illus-

trated in the accompanying drawings, and particularly pointed out in the appended claims.

Figure 1 is a side elevation of a bath tub showing the rail attached to its rim; 60

Fig. 2 is a plan view of the hand rail as applied to a tub rim;

Fig. 3 is a detail of one of the fastening devices;

Fig. 4 is an enlarged detail view of the 65 front fastening;

Fig. 5 is a view of Fig. 4 looking toward the left, parts being broken away;

Fig. 6 is a detail view of the wall bracket;

Fig. 7 is a cross section on the line 7—7 70 of the modified form of rail fastening shown in Fig. 8;

Fig. 8 is a cross section on the line 8—8, Fig. 7.

As bath tubs are ordinarily placed adjacent a wall, the rim of the tub 1 to which the hand rail is shown affixed, will be designated as the rear rim 2. In this selected embodiment, the bath rail consists of two members, the rear rail 3 and the cross rail 4. 75 The rear rail extends longitudinally the tub and is secured thereto by the clamps 5 while the cross rail, pivotally secured to the rear rail, extends across the tub and is secured to the front rim by means of the clamp 6. Both 80 rails are suitably roughened to assure a good friction grip and, to this end, have knurled surfaces extending the major portions of their lengths. The parts 7 of both rails are 85 substantially smooth and offer facile means 90 of slidably adjustable engagement of the clamps thereon.

The rear clamps 5 are similar and each 95 comprises a relatively fixed member 8 and the movable arm 9. The member 8 is substantially arched in shape and has an inner depending lip 10 and an outer upwardly projecting lip 11. The arm 9 is pivotally mounted between integral ears 12 of the fixed member and is provided with a shoulder 13. The knurled-headed set screw 14, received in threaded engagement in a longitudinal rib 15 integral with the fixed member 8, is adapted adjustably to impinge upon the shoulder 13. The mode of adjustably positioning the clamp 5 upon a tub rim is 100 shown in Fig. 3.

The clamps thus are provided each with a three-point bearing on the tub—a type of bearing which, as is well known, permits of 105

a wide range of adaptability to variant tub forms and sizes coincident with a high degree of retentivity. The edge of the rim 2 is received within and bears against the support formed on the arched member by the upwardly presented lip 11; the depending lip 10 bears upon the rim at that portion which downwardly curves to form the tub side; while the arm 9, which adjustably and tensionably impinges upon the outer tub side, forms the third bearing point. The member 8, sufficiently arched to accommodate varying degrees of rim curvature, is shown, in this selected embodiment, as having a substantial clearance above the rim 2 of the tub. In such manner each clamp is positioned on the tub and is retentively affixed thereon by turning down the screw 14—the end of which, impinging upon the integral shoulder 13 of the pivoted arm 9, forces the arm end positively against the outer tub side as shown in Fig. 3, and thus effectuates the clamping function.

The rail 3 is slidably received within the sleeves 16 and may be retained therein by means of set screws 17. Each sleeve 16 has a swiveled mounting upon the fixed member 8 in order to allow for necessary angular adjustment when the clamps are positioned upon portions of the tub rim not in the same straight line, for example, when one of these clamps is placed upon the rim as it curves to form the front or rear of the tub. The sleeve 16 has an interiorly threaded reduced portion 18 which is received within an aperture in the arched member 8. A screw 19, having a washer 20, is received in threaded engagement within the reduced portion 18 and functions to retain the sleeve movably seated upon the arched member.

The cross rail 4 at its rear end terminates in a sleeve 21 preferably integral therewith which is adapted to receive therethrough the longitudinal rail. The cross rail may be held against movement thereon by means of the set screw 22. The forward end of the cross rail is detachably secured to the clamp 6. The clamp 6 is similar in structure to the clamps 5 except, instead of the sleeve, it bears a similarly mounted swiveled yoke 23 between the two members of which is pivotally mounted the socket 24. The upper portion of this socket is slightly constricted so that the cross rail is retained therein against vertical dislodgment.

When this device is used in connection with shower bath apparatus the cross rail is disengaged from the clamp 6, is swung, by means of its sleeve 21, about the longitudinal or rear rail 3 into substantially upright position where it is retained by means of a bracket 25 suitably affixed to an adjacent wall. The bracket 25 consists of a fixed member 26 to which is pivotally

secured the strap 27 having a binding screw 28 adapted to be received in threaded engagement with the fixed member.

A modified form of the clamping member which is used to secure the hand rail to the tub is shown in Figs. 7 and 8. This type is adapted to be used when the tub rim is positioned so closely against a wall that it is impracticable to secure the adjustable clamps thereon. Or it may be used with tubs of the general type indicated in Fig 8 in which the tub rim extends to the floor or a substantial portion of the way thereto. In this form the rail receiving sleeve 29 is provided with a stem 30 which is threaded 80 to receive in engagement therewith the nuts 31 and 32. The plate 33 suitably apertured therefor is adapted to be positioned upon the stem 30 between the nuts. The rim 34 of the tub has an aperture 35 adapted 85 to receive the nut 32. A slot 36 leads from the aperture 35 a short distance on the tub rim as is indicated in Fig. 7. To secure this rail engaging sleeve to the rim the stem bearing the nuts is inserted in the aperture 90 and is slipped along the slot assuming the position shown in Fig. 7 in which the lower nut 32 impinges upon the under face of the rim adjacent the slot while the plate 33 functions to cover the slot and aperture and 95 to prevent the access of water thereto. Upon the turning down of the upper nut 31 the sleeve is retentively secured to the rim when the hand rail may be inserted in the sleeve 29 and thus retained adjacent the tub rim. 100

This invention thus provides a structure which is readily and easily adaptable to divers sizes and shapes of bath tubs. It is of the utmost simplicity of adjustment, has a low productive cost and it efficiently 105 accomplishes its function both when used with the ordinary bath tub appliances and when used in connection with shower bath apparatus.

It is to be understood that the construction disclosed herein is illustrative but not restrictive and that the same may be modified within the meaning and scope of the claims which follow.

Having fully described my invention, 115 what I claim as new and desire to secure by Letters Patent is:

1. The combination of a bath tub with a hand rail extending longitudinally the tub, means for securing the rail to the tub, 120 a cross rail extending transversely the tub, and means for securing the cross rail on the tub.

2. The combination of a bath tub with a hand rail extending longitudinally the tub, 125 means for adjustably securing said rail to the tub, a cross rail extending transversely the tub, and means for adjustably securing the cross rail to the tub.

3. The combination of a bath tub, a longi-

130

5. The tub rim to receive one end of the cross rail, and means for pivotally securing the other cross rail end on said longitudinal rail whereby said cross rail may be turned on the longitudinal rail to afford an upright hand rail.
4. The combination of a bath tub, a longitudinal rail and a cross rail, means for adjustably securing said longitudinal rail to the rim of one side of the tub, means for securing one end of said cross rail to said longitudinal rail, means for detachably securing the second end of said cross rail to the other tub side rim and means fixed above said tub adapted adjustably to retain said second cross rail end whereby said cross rail may be swung about said longitudinal rail into upright position and there retained.
5. The combination of a bath tub, hand rails therefor, and a plurality of rail-engaging clamps adapted adjustably to be secured on the rim of said tub, said clamps each comprising an arched member adapted substantially to fit said rim and a pivoted adjustable member adapted tensionably to impinge against the adjacent tub side, whereby said rails are detachably secured to said tub rim.
6. The combination of a bath tub, hand rails therefor and a plurality of rail-engaging clamping members adapted adjustably to be secured to the rim of said tub, a sleeve mounted on each of said members to receive and retain said rails, said sleeves being swiveled to allow for angular rail adjustment when said clamping members are affixed to the curved portions of said rims adjacent the tub ends.
7. The combination of a bath tub, hand rails therefor and a plurality of rail-engaging clamps adapted adjustably to be secured to the tub rim, each comprising an arched member, a sleeve swiveled to said member and adapted to receive therein a rail portion, ears on said arched member, a movable arm pivotally mounted between said ears, a shoulder on said arm, a set screw carried in threaded engagement on said member and adapted adjustably to impinge on said shoulder to cause said arm to be forcibly pressed against the side of the tub whereby said rail may be secured to said tub.
8. The combination of a bath tub, a longitudinal rail adjustably secured to a tub rim, a cross rail having a sleeve at one end adapted to receive therethrough said longitudinal rail to permit said cross rail to be turned thereon through an arc in a plane substantially normal to said longitudinal rail, a clamping member adapted to be adjustably secured to the side of the tub opposite said longitudinal rail, a forked support swiveled on said member, a socket pivotally mounted between the forks of said support and adapted to receive and retain the other end of the cross rail.
9. The combination of a bath tub, a longitudinal rail and a cross rail, means for securing the longitudinal rail to the rim of the tub side, means for adjustably securing one end of the cross rail to the opposite tub rim and means for pivotally securing the other cross rail end to the longitudinal rail whereby said cross rail may be turned on the longitudinal rail to afford an upright hand rail.
10. The combination of a bath tub, a hand rail extending longitudinally one side of the tub, supporting members therefor, each comprising an arched shaped member adapted to embrace the edge of the tub, a shouldered member pivotally attached thereto adapted to engage the edge of the tub rim and the adjacent side of the tub and a screw-threaded member adapted to lock the rim engaging member in position, a yoke pivotally mounted on said arched member and a rail receiving member pivotally mounted on said yoke.
11. The combination of a bath tub, a longitudinally extending rail, rail supporting means consisting of an arched clamping member having a pivotally mounted shouldered extension adapted to engage the edge of the tub rim and the adjacent side of the tub, means for locking the same and a member adapted to receive and hold the longitudinal rail.
12. The combination of a bath tub, a longitudinally extending rail, rail supporting means consisting of an arched member and an extension pivotally mounted thereon having oppositely disposed shoulders adapted respectively to engage the tub rim and a locking screw and means swiveled upon said extension to receive said longitudinally extending rail.
13. The combination of a bath tub, a longitudinally extending rail, a cross rail, rail supporting means consisting of an arched clamping member having a pivotally mounted shouldered extension adapted to engage the edge of the tub rim and the adjacent side of the tub, means for locking the same and a member adapted to receive and hold the longitudinal rail, a socket member adapted to be adjustably and pivotally secured to the opposite tub rim and adapted to receive and hold one end of the cross rail.
14. An adjustable clamp adapted to be secured to the rim of a tub comprising an arched member having a projection adapted to bear upon the tub rim and a projection adapted to engage the edge of the tub rim whereby said arched member has a substantial clearance above the tub rim, means

adapted to secure said arched member to the tub rim, and supporting means pivotally mounted on said arched member.

15. An adjustable clamp adapted to be secured to the rim of a tub comprising an arched member having a projection adapted to bear upon the tub rim and a projection adapted to engage the edge of the tub rim whereby said arched member has a substantial clearance above the tub rim, a lever arm pivotally mounted on said arched member, and means on said arched member adapted forcibly to press said arm against the adjacent tub side whereby said clamp is securely retained on the tub rim.

16. An adjustable clamp adapted to be secured to a tub rim comprising an arched member, swiveled supporting means carried by said member, a shoulder on said member adapted to bear upon the tub rim and a pro-

jection on said member adapted to engage the end of the tub rim, ears on said arched member, a movable arm pivotally mounted between said ears, a shoulder on said arm, a set screw carried in threaded engagement on 25 said member and adapted adjustably to impinge on said shoulder to cause the movable arm to be forcibly pressed against the side of the tub whereby said clamp may be secured to the tub rim.

17. An adjustable clamp adapted to be secured to a tub rim comprising an arched member, means on said arched member adapted to secure said member to each rim, a forked member pivotally mounted on said 30 arched member, and supporting means pivotally mounted on said forked member.

In testimony whereof I have signed my name to this specification.

BENJAMIN F. BROWN.
